ATTORNEY.

UNITED STATES PATENT OFFICE.

WILLIAM A. ALLEN, OF COLFAX, TEXAS.

STALK-KNOCKER.

SPECIFICATION forming part of Letters Patent No. 372,735, dated November 8, 1887.

Application filed August 8, 1887. Serial No. 246,435. (No model.)

To all whom it may concern:

Be it known that I, WILLIAM A. ALLEN, a citizen of the United States, residing at Colfax, in the county of Van Zandt, State of Texas, have invented certain new and useful Improvements in Stalk-Knockers, of which the following is a specification, reference being had therein to the accompanying drawings.

This invention has relation to stalk-knockers, and among the objects in view is to provide a stalk-knocking mechanism that is simple of construction, effective in operation, cheap, and which is adapted to be applied to the running-gear of an ordinary farm-wagon.

Other objects and advantages will be herein-after described, and the novel features of the invention will be particularly pointed out in the claims.

Referring to the drawings, Figure 1 is a side elevation of the running-gear of an ordinary farm-wagon with the body removed and provided with a stalk-knocking mechanism constructed in accordance with my invention. Fig. 2 is a rear elevation of the same; and Fig. 3 is a modification in perspective, hereinafter referred to.

Like letters of reference indicate like parts in all the figures.

A A' represent the front and rear wheels, respectively, of a wagon, A² the axle, A³ the reach, and A⁴ the bolsters, all of the usual construction.

B represents an oblong frame-work, consisting of side and end rails, B' B'', which are mortised and bolted at each corner, as at B³. This frame-work B is mounted upon the bolsters A⁴ of the wagon, the body of the same having been previously removed, and may be retained in position on said bolsters by any suitable devices, such as pins, bolts, &c. The rear end of the frame-work at each side is provided with longitudinal slots B⁴, having opposite pin-holes or perforations, B⁵; and adjustable in the slots, and retained in position by means of pins B⁶, passed through said holes, are depending hangers C, having at their lower ends bearings C', (in this instance open at one side,) and provided at their upper ends with a series of adjusting-holes or apertures, C², adapted to receive the pin B⁶, and thus be raised or lowered to any desired height from the ground.

An inclined brace-rod, D, perforated as at D', is pivotally connected to the lower portion

of each of the hangers C, as at D², said brace being adjustable within the frame-work by means of a pin, D³. By this arrangement of 55 the brace the hangers may be swung away from or nearer to the rear wheels, A', the object and purpose of which will be apparent.

The wheels A' may be provided with a grooved or plain pulley, E, secured thereto in 60 any suitable manner; but in this instance, and in order to provide an ordinary wagon-wheel with a drive-pulley, I prefer to form the pulley-wheel in sections E' in the form of an arc of a circle. These sections are preferably cast- 65 iron, and are formed with the oppositely-disposed lugs or ears E'', adapted to embrace two adjacent spokes of the wheel, and when thus in position to form a continuous pulley or drive-wheel. The sections shown in Fig. 1 are introduced with their lugs between two adjacent 70 spokes near the rim of the wheel, and are then, by pressure or taps upon their tops, driven down and seated firmly between the spokes, wedging in between the same. Several of these sections being placed in position, their ends may be secured by metallic straps or clips E'.

Journaled in the open bearings C' of the hangers C is the knocker-shaft F, (in this instance formed with the bearings or journals F',) 80 having radiating knockers F² at each end, and a similar intermediate knocker. Small pulleys F³ are formed at each side of the shaft, and from these and over the drive pulleys or wheels E extend a rope belt, or it may be a belt of any 85 desired character, G. By this arrangement it is apparent that when the wagon is in motion, motion will be given from the pulley E through the belt G to the pulley F³ and its shaft, rotating the knockers and thus clearing a field of 90 stubble and stalks.

In Fig. 3 of the drawings I have illustrated a form of pulley-section whereby the same is adapted to fit any size wheel. In this instance the lugs for embracing the spokes are disposed toward each other, and the section is introduced near the hub and driven upwardly toward the rim of the wheel. The sections are preferably made somewhat shorter than in the construction previously described, so that 95 generally there is a space between the same. The sections in this instance are secured to each other as in the other form—namely, by the metallic straps or clips E'. In the modi-

fication the straps are made longer, and are provided with a series of perforations in order that the sections may be as far apart as the size of the wheel will require.

5 By the adjustable brace-rod D the hangers may be adjusted so as to keep the belt taut upon the pulleys.

Having described my invention and its operation, what I claim is—

10 1. The combination, with the running-gear of a wagon, of a frame-work mounted thereon and provided with vertically-adjustable hangers at its rear end carrying stalk-knockers and their shaft, a diagonal adjustable brace connecting

15 the hanger and the frame-work, and a driving pulley formed in sections, having spoke-embracing lugs, and connected to the knocker-shaft by means of a belt, substantially as specified.

20 2. The frame B, slotted as at B⁴, and having the hangers C, adjustable in said slots, and pro-

vided with bearings C', having the shaft F, carrying knockers F², in combination with the pulley E, formed in sections E', connected as at E³, and having lugs E² for embracing the 25 spokes, said pulley and shaft being connected by the rope or belt G, substantially as specified.

3. The combination, with the rear wheels of a wagon, of a pulley-wheel mounted thereon, and comprising sections in the form of arcs of a circle and having lugs for embracing the spokes and adapted to be wedged thereon, a frame-work, depending knocker-shaft carrying hangers, and a belt connecting the shaft and pulley, substantially as specified. 30

In testimony whereof I affix my signature in presence of two witnesses.

WILLIAM A. ALLEN.
